Specification for Design.

Patented Oct. 14, 1913.

Application filed February 3, 1913. Serial No. 746,060. Term of patent 14 years.

To all whom it may concern:

Be it known that I, WILLIAM W. DUNCAN, a citizen of the United States, residing at Watertown, in the county of Middlesex and State of Massachusetts, have invented a new, original, and ornamental Design for Vehicle-Tires, of which the following is a specification, reference being had to the accompanying drawing, forming part thereof.

Figure 1 is a perspective view of a vehicle

tire showing my new design; and Fig. 2 is a developed plan view of a portion thereof on a larger scale.

I claim:

The ornamental design for a vehicle tire, as shown.

WILLIAM W. DUNCAN.
